DESIGN FOR A PHOTOGRAPHIC MOUNT OR THE LIKE

Jack Hecht, New Haven, and Walter G. Klubek,
Derby, Conn.

Application June 5, 1942, Serial No. 107,137

Term of patent 7 years

To all whom it may concern:

Be it known that we, Jack Hecht and Walter G. Klubek, each a citizen of the United States, residing respectively at New Haven and Derby, in the county of New Haven and State of Connecticut, have invented a new, original, and ornamental Design for a Photographic Mount or the like, of which the following is a specification, reference being had to the accompanying drawing, forming part thereof.

The figure is a plan view of a photographic mount or the like, showing our new design. The thickness of the article is conventional.

We claim:

The ornamental design for a photographic mount or the like, as shown and described.

JACK HECHT.

WALTER G. KLUBEK.
